UNITED STATES PATENT OFFICE.

CHARLES B. MOORE, OF EVANSTON, ILLINOIS, ASSIGNEE, BY MESNE ASSIGNMENTS,
TO AMERICAN ARCH COMPANY, OF NEW YORK, N. Y., A CORPORATION OF DELA-
WARE.

LOCOMOTIVE-BOILER FURNACE.

1,138,052.

Specification of Letters Patent.

Patented May 4, 1915.

Application filed February 14, 1912. Serial No. 677,568.

To all whom it may concern:

Be it known that I, CHARLES B. MOORE, a citizen of the United States, and a resident of the city of Evanston, county of Cook, and 5 State of Illinois, have invented certain new and useful Improvements in Locomotive-Boiler Furnaces, of which the following is a specification.

My invention relates to improvements in 10 locomotive boiler fireboxes and has particular reference to improvements in refractory baffles or deflecting walls commonly called arches for the fireboxes of locomotives.

The general objects of my invention are 15 to provide an arch for locomotive boilers which can be easily and quickly built; which can be as easily and quickly dismembered or removed; which shall be of comparatively light weight and low cost; and parts of 20 which can be readily removed for the repair of the firebox.

A further object of my invention is to provide an arch of the above construction particularly adapted for installation in locomotive boilers equipped with a plurality of water-circulating tubes.

My invention consists in the several improvements, the various features of construction and the combinations of parts by 30 means of which the above and other objects are attained and all as hereinafter described and pointed out in the appended claims.

My invention will be more readily understood by reference to the accompanying 35 drawings forming part of this specification, and in which:

Figure 1 is a central vertical longitudinal section of a locomotive firebox equipped with a refractory arch the whole embodying my 40 invention; Fig. 2 is an enlarged transverse sectional view on the line 2—2 of Fig. 1; Figs. 3, 4 and 5 are perspective views of several of the refractory saddles or supporting members; and Fig. 6 is a fragmentary sectional view similar to Fig. 2 illustrating a 45 modified form of saddle.

Refractory arches are made use of in locomotive boiler fireboxes for different specific results and although I have confined the 50 illustration of my invention to a so-called front arch, it should be understood that my invention is not limited to an arch occupying this particular position and having the specific functions of such arches. A so-called 55 front arch usually occupies an inclined po-

sition in the forward end of the firebox, arranged between the fuel bed and the flues and its principal functions are to baffle and deflect the rising firebox gases and prevent the direct flow of said gases from the fuel 60 bed to the flues, thereby causing them to flow backward and forward in the firebox and distribute their heat over substantially the entire interior surface of the firebox and particularly throughout the length of the 65 crown sheet. Arches made in accordance with my invention not only retain the above desirable features but also assist in the commingling and admixing of the firebox gases and thereby prevent the stratification 70 thereof.

A locomotive firebox as shown in the drawings consists of a flue sheet 2 at its forward end, side sheets 3, 3, a rear sheet 4 having a fuel door or opening 5 and a crown 75 sheet 6. The firebox is provided with a grate 7. Flues 8 lead forward from the flue sheet. The firebox illustrated is provided with a number of water-circulating tubes 9, the same being inclined upwardly and rearwardly from the lower portion of the flue sheet to the upper portion of the rear sheet and serving to increase the circulation of water between the front and rear water legs of the boiler, as well as aiding in the rapid 80 production of steam. I make use of these inclined water-circulating tubes as a foundation upon which to build my arch. Front arches usually have their front end in abutment with or close to the flue sheet and consequently when the forward end of the tubes are relatively close to the grate, it is desirable to space the forward end of the arch above the tubes to the end that the space 85 between the arch and the grate may be sufficient to accommodate the fuel bed and afford proper space for the proper circulation of the gases between the fuel bed and the arch. Furthermore, the water-circulating tubes ordinarily used in locomotive boilers have usually relatively thin walls and as they extend 90 from the flue sheet to the rear sheet of the firebox, they can be comparatively easily sprung out of their proper positions and as the refractory arch which is supported by 95 these tubes is relatively heavy, the tubes must be protected from being distorted by the weight of the arch. In my novel form of arch construction, I protect the tubes 100 from this distorting effect by means of re- 110

refractory arch saddles or supports, which I place upon the tubes and I use these saddles as the supports for the bricks of which the arch itself is composed and these bricks lie in a plane above the plane of the tubes and are wedged between the side sheets of the firebox. They are supported in their raised position by the refractory saddles which rest upon the upper surfaces of the tubes and consequently the strains necessary to hold bricks of the arch transversely in the firebox, are not transmitted to the tubes themselves and therefore the tubes are not forced out of their normal positions but are free to assume positions in which they are not subject to distorting strains due to the wedging action of the arch.

The firebox illustrated is provided with four of the arch supporting tubes 9 and I provide refractory saddle bricks 10 for placement upon the tubes. These saddle bricks are relatively narrow and have a tube-receiving groove 11 formed in their undersides. They also have a semi-cylindrical projection 12 upon their upper sides arranged parallel with the groove 11 and preferably of about the same radius. These saddle bricks are also provided with laterally extending flanges 13 providing marginal shoulders 13' one on each side upon which arch bricks 14 are adapted to rest. The arch bricks themselves are provided with sockets 14' at their ends which substantially fit the projections 12 of the saddle bricks, and the transverse ends 15 of the arch bricks above the saddle bricks are inclined inwardly so that when the bricks are in position as shown in Fig. 2, a V-shaped crack or opening 16 is provided between the ends of adjacent bricks. The saddle bricks are provided in their upper sides with V-shaped splitting or cracking grooves 17 which practically form extensions of the V-shaped grooves 15 between the transverse ends of the arch bricks when said bricks are in place. The saddle bricks as illustrated may be tapered from end to end so that when placed in position they will support one edge of the arch bricks higher than the other edge and I commonly make use of supporting bricks of different thicknesses or heights arranged end to end as illustrated so arranged that they form substantially continuous refractory arch saddles or supports with their upper or brick receiving surfaces inclined at a different angle from the angle of the tubes upon which the arch rests. This construction lends itself readily to the production of an arch having its forward end raised farther away from the tubes than its rear end as shown in Fig. 1.

A further advantage is that the arch itself can be built of arch bricks which can also be used for building arches directly upon the tubes themselves without the interven-

tion of the refractory saddles so that but one form of arch brick need be provided for building arches which either rest upon the tubes themselves or upon the refractory saddles; that is, the grooves or sockets 14' in the transverse edges of the arch bricks are adapted to fit either the tubes or the semi-cylindrical projections or abutments 12 of the saddle bricks. The individual bricks of the arch are limited in size by the features that they shall not be too bulky or heavy to be readily placed in position; that they shall be capable of being readily passed through the fire door and also that they shall be as large as consistent with these limitations to the end that the arch itself shall be composed of as few individual members as possible. The arch bricks 14 are provided with relatively large gas mixing pockets or pits 14" in their under surfaces which reduce their weight without materially reducing their strength, consequently, the arch as a whole is comparatively light. The gas mixing pockets 14" also serve the purpose of providing the under side of the arch with a plurality of gas mixing recesses and deflecting walls which enhance the intermingling of the gases of combustion and in producing perfect combustion within the firebox.

It sometimes occurs that the arch tubes 9 are not exactly parallel with each other as the position of these tubes depends to some extent upon the position of the stay bolts in the firebox and consequently when this occurs, the refractory arch supports which rest upon the tubes are not evenly spaced and therefore the arch bricks 14 do not properly fit in position. To overcome this difficulty, I provide the form of saddle brick illustrated in Fig. 6 provided with a laterally widened tube receiving groove 17, whereby the saddle brick, in a practical sense, floats upon the tube and is free to adjust itself in accordance with the positions of the arch bricks and without producing any lateral or transverse strain upon the tubes.

In building arches in accordance with my invention, after the saddle bricks have been placed in position upon the tubes I arrange the arch bricks in transverse rows reaching from side sheet to side sheet, the first row in substantial abutment with the floor sheet. The rows comprise middle members which rest at each end upon saddles and marginal members 18 which rest at their inner ends upon a saddle member and at their outer ends are supported by one of the side sheets. These marginal bricks 18 are arranged in upwardly and outwardly inclined positions wedgeingly engaging the side sheets and the refractory support upon which they rest and they thereby serve to lock the whole arch body transversely in the firebox between the side sheets.

side sheets. I complete the arch to the length desired by adding additional transverse rows of the arch bricks above the first row and supported thereby. The arch can be made of any suitable length, sometimes but two transverse rows being sufficient to produce the desired results. The arch having been formed and having been operated for some time, the arch bricks and the refractory supporting bricks become more or less thoroughly cemented together and thereafter when it is desired to remove portions of the arch for the purpose of repair, the bricks of the arch can be readily broken apart by driving wedges into the V-shaped grooves 15. If they are thoroughly fused to the refractory arch supports, these supports themselves can be readily split or broken apart upon the fracture line provided by the breaking or cracking grooves 16.

As many modifications of my invention will readily suggest themselves to one skilled in the art, I do not limit or confine my invention to the specific structures herein shown and described.

I claim:

1. In a locomotive boiler firebox having a plurality of substantially parallel water-circulating tubes, a refractory arch composed of a plurality of refractory slab-like arch bricks arranged across the firebox the end bricks of each row being wedgingly engaged with a side sheet of the box, refractory supporting members formed for placement upon the tubes and serving to support said bricks above the plane of the tubes, said supporting members having semi-cylindrical projections on their upper surfaces and said bricks having complementary sockets on their ends receiving said projections, the upper portions of the ends of said arch bricks being inclined inwardly whereby V-shaped grooves are provided between the ends thereof.

2. A locomotive boiler firebox having a plurality of substantially parallel water-circulating tubes, in combination with a refractory arch supported by said tubes and extending from side sheet to side sheet, said arch comprising a plurality of longitudinal rows of bricks each row spanning the space between two tubes or between a tube and a side sheet, and refractory supporting members resting upon said tubes and supporting said rows at their edges, the bricks of said rows being beveled at their ends to provide V-shaped grooves between the adjacent edges of the rows and said supporting members having V-shaped grooves forming continuations of the spaces between said rows.

3. A locomotive boiler firebox having a plurality of substantially parallel water-circulating tubes, in combination with a refractory arch supported thereby and extending from side sheet to side sheet, said arch comprising refractory supporting members lon-

gitudinally arranged upon said tubes and refractory arch bricks arranged in transverse rows extending from side sheet to side sheet, said arch bricks having their adjacent ends separated to form longitudinal grooves in the arch and said supporting bricks having V-shaped grooves in their upper surfaces forming continuations of said longitudinal grooves and thereby providing the arch with weakened breaking lines.

4. A locomotive boiler firebox having a plurality of substantially parallel arch supporting tubes, in combination with a refractory arch therein extending from side sheet to side sheet and wedgingly interposed therebetween, said arch comprising a plurality of supporting members arranged upon said tubes and a plurality of transverse rows of arch bricks spanning from supporting member to supporting member and resting at their ends thereon, said supporting members being provided with grooves in their upper edges forming fracturing lines in said arch disposed above said tubes.

5. A locomotive boiler firebox containing a plurality of inclined substantially parallel water-circulating tubes, in combination with a refractory front arch therein extending from side sheet to side sheet and resting against the flue sheet and comprising a plurality of refractory arch supports arranged upon said tubes and a refractory arch proper resting upon said supports and thereby held above the plane of the tubes, the said supports beneath the forward end of the arch proper being higher than those beneath the rear end of the arch proper.

6. A locomotive boiler firebox containing a plurality of inclined substantially parallel water-circulating tubes lying in substantially a single transverse plane, in combination with a refractory front arch wedgingly interposed between the side sheets of the firebox and resting against the flue sheet, the arch proper being inclined relatively to the tubes with its forward edge supported farther from the tubes than its rear edge and tapered refractory arch supports interposed between the arch and the tubes and supporting the arch in such position.

7. A refractory arch brick for placement upon a water-circulating tube in a locomotive firebox comprising an elongated member having a longitudinally arranged tube receiving socket or groove in its lower face and a longitudinal brick receiving projection on its upper face, said projection being provided with a V-shaped crack or slot in its upper part.

8. A refractory supporting member for locomotive arches comprising an elongated refractory brick having a longitudinally arranged tube receiving socket or groove in its lower face, laterally extending supporting flanges on its edges and a longitudinal semi-

cylindrical projection on its upper side, said projection having a V-shaped cracking slot in its upper surface.

9. A locomotive boiler firebox, containing
5 a plurality of longitudinally arranged water
circulating tubes lying in a transverse plane,
in combination with a refractory arch
proper arranged above said tubes and ex-
tending from side to side of the firebox, the
10 arch proper being longitudinally inclined
relatively to the tubes, and narrow, elon-
gated refractory arch supports having tube

receiving grooves in their lower sides and
resting upon said tubes and maintaining the
arch proper in its relatively inclined po- 15
sition.

In testimony whereof, I have hereunto set
my hand, this 24th day of January 1912, in
the presence of two subscribing witnesses.
